UNITED STATES PATENT OFFICE.

GEORGE WM. WOOD, OF CAMDEN, NEW JERSEY, ASSIGNOR OF ONE-HALF TO MICHAEL SHAPIRO, OF CAMDEN, NEW JERSEY.

FURNACE-TILE.

979,627.

Specification of Letters Patent. Patented Dec. 27, 1910.

Application filed February 23, 1910. Serial No. 545,378.

To all whom it may concern:

Be it known that I, GEORGE W. WOOD, a citizen of the United States, residing at Camden, in the county of Camden and State 5 of New Jersey, have invented certain new and useful Improvements in Furnace-Tiles, of which the following is a specification.

My invention relates to improvements in furnace tiles and more particularly to tiles 10 which are adapted to be supported against and between the lower set of tubes of a tubular boiler and constitute, not only baffles but also to be heated to a high state of incandescence, so as to consume the otherwise 15 waste products of combustion.

A further object is to provide improved tile or brick which will be so shaped that they may be readily positioned between the boiler tubes to be self-supporting on the 20 boiler tubes, and which may be adjusted so as to regulate the area through which the smoke and gases from the fire box will pass.

With these and other objects in view, the invention consists in certain novel features 25 of construction, and combinations and arrangements of parts as will be more fully hereinafter described and pointed out in the claims.

In the accompanying drawings: Figure 1, 30 is a fragmentary view in section through a fire box, showing the boiler tubes in elevation, and illustrating my improved tile in position. Fig. 2, is a detailed perspective view of one of the tile, and Fig. 3, is a fragmentary plan view of the lower set of boiler tubes, with my improved brick or tile in position. Fig. 4, is a view in section on the line 4, 4, of Fig. 3.

1 represents the fire box or combustion 40 chamber of an ordinary steam boiler furnace, and 2, are the boiler tubes disposed at an incline, and supported on the usual bridge wall 3.

4, represents my improved tile or brick, 45 one tile or brick being shown in perspective in Fig. 2.

By reference to Figs. 3, and 4, it will be seen how the tile are assembled between the boiler tubes 2, each tile which is of general 50 rectangular form, is provided in one face with a longitudinal groove or recess 5, curved in the arc of a circle in cross section so as to fit snugly against the tube 2.

The tiles 4, are arranged back to back 55 with their flat backs engaging and their

grooved faces fitting against the tubes, one tile must be placed in position at a time, against its tube and when moved longitudinally so as to bring its back against the back of a tile already placed, the two will serve 60 to hold each other. The tiles are moved so that openings are left between the ends of the tile through which the smoke and gases pass. As the tile are located between the lowest set of boiler tubes, they are in close 65 proximity to the fire, and receive the intense heat which serves to heat the brick or tile to a high state of incandescence, so that the tile not only serve to baffle the smoke and gases, but by reason of the high temperature 70 they attain, the gases will be consumed when contacting with the tile, so that heat units will be utilized, which would otherwise be lost.

While the grooves 5, might be located exactly in the vertical centers of the tile, I prefer to locate them slightly nearer the upper than the lower edges of the tile, thus rendering the lower portion of the tile 75 slightly thicker to better withstand the intense heat to which they are subjected.

The tile or brick may be made of various refractory materials, but preferably of a material to withstand the greatest heat.

Various slight changes might be made in 80 the general form and arrangement of parts described without departing from my invention, and hence I do not limit myself to the precise details set forth, but consider myself 85 at liberty to make such changes and alterations as fairly fall within the spirit and scope of the appended claims.

Having thus described my invention what I claim as new and desire to secure by Letters Patent is:

1. The combination with boiler tubes, of two longitudinal series of bricks interposed between parallel facing boiler tubes, and having grooved faces engaging the boiler tubes, and flat backs, said bricks arranged in 90 staggered relation, with the flat backs of one series engaging the flat backs of the other series, and the bricks of each series spaced apart, substantially as described.

2. The combination with boiler tubes, of two longitudinal series of bricks interposed between parallel facing boiler tubes, and extending above and below the tubes, all 100 of said bricks having grooved faces longitudinally of the bricks, between their up- 105

per and their lower edges to engage the boiler tubes, and flat backs, said bricks arranged in staggered relation, with the flat backs of one series engaging the flat backs of the other series, and the bricks in each series spaced apart, substantially as described.

In testimony whereof I have signed my name to this specification in the presence of two subscribing witnesses.

GEORGE WM. WOOD.
